C. R. KRONE

ELECTRIC SWITCH

Filed March 22, 1926

Fig. 11.

UNITED STATES PATENT OFFICE.

CARL RUDOLPH KRONE, OF OAKLAND, CALIFORNIA.

ELECTRIC SWITCH.

Application filed March 22, 1926. Serial No. 96,580.

This invention relates to a pinion gear contact electric switch, adapted to connect and disconnect different segments of an internal gear, to be mechanically controlled 5 from a revolving shaft.

An object of my present invention is to provide a mechanism which will operate electric signals in response to the customary motions of the steering wheel of a motor vehicle, when it is pursuing a course straight ahead or one deviating to the right or left.

With the foregoing objects in view, together with such others as may subsequently appear, this invention resides in the construction and cooperation of parts herein-after described and claimed, and illustrated in the accompanying drawings, in which:

Figure 1 is a perspective view of my improved pinion gear contact switch mechanism in cooperation with the usual steering apparatus of a motor vehicle, which is pursuing a straight ahead course;

Figure 2 is a plan view of my switch partly broken away, and of the correlated parts, members and attachments outside of the casing, as they appear when the steering wheel is turned sufficiently to effect a deviation to the right from the straight ahead course of the vehicle;

Figure 3 is a section on the line 3—3 of Figure 2 but the steering wheel returned to straight ahead position in agreement with Figure 1, the line 3—3 indicating the horizontal projection of the main plane of symmetry of the system;

Figure 4 is a perspective view of a switching member employed in my device; and

Figure 5 is a perspective view of a member adapted to actuate the switching member shown in Figure 4.

Referring to the drawings for a description thereof, the numeral 7 indicates a flat columnar switch casing provided with a cover 8, both of insulating material, and both symmetrically disposed to line 3—3.

The casing 7 is secured to the housing 10 by a looped strap 11, and a grooved band 11' having a central aperture 11'', as shown in Figures 2 and 3. The looped ends 12 of the strap 11 are hooked to the U-shaped loops 13, which are secured to the rim of the casing. A pin 17 issues from an aperture 7' and a grooved portion 7'' of the rim, to pass through the aperture 11'', and through an aperture 10' of the housing 10, as shown in Figure 3. A bolt 16 passing

along the groove 7'', engages an aperture 17' of pin 17 and two perforations 15 of the strap 11. Nuts 16' are threaded on the bolt 16 and provided for tightening the 60 strap 11.

An electrically conducting internal gear, comprising a plurality of spaced, insulated segments 21, 22, 23 and 24, is secured to the floor and the tubular walls of the casing. 65 An electrically conducting wire is connected to each of the segments 22, 23 and 24, and segment 23 is a live segment, while segments 22 and 24 are contact segments adapted to be connected with a signalling device. 70 The smallest segment 21 lies across the rim from the pin 17, the largest segment 23 lies diagonally across from segment 21.

A metallic plate 18 lies centrally upon the floor of the casing and electrically connects 75 the segments 23 and 21, by means of integral, material extensions, as live members.

Three pivoted, metallic pinions 35, 36 and 37 lie in mesh with the segments 21 and 23 respectively, and with flat contact upon the 80 plate 18, with freedom of motion thereon and upon the extensions of the same.

Two short pins, rising from the segments 22 and 24 at the positions 26' and 28' respectively, are adapted to restrict the pinion 85 35 from progress beyond the segments 22 and 24.

A metallic drive gear 29, fixedly mounted on an insulating pin 31, lies on the plate 18 with freedom of motion thereon. The drive 90 gear 29 is adapted to mesh with the pinions 35, 36 and 37.

A metallic frame plate 30 is provided with apertures 40, spaced on a circle and adapted to rotatably confine the pivots of the pinions, and also provided with a central aperture 31', adapted to rotatably confine the pin 31 of the drive gear. The frame plate 30 functions to adjust the pitch 95 line of the combined pinions 35, 36 and 37 100 to the pitch line of the internal gear, and to hold the pinions at optimal distance from the drive gear. A peripheral extension 33 of the plate 30 is adapted to engage the short pins at the positions 26' and 28' and to effect the restriction of the pinion 35 to pass beyond the segments 22 and 24 respectively.

The casing 7 has a recess 42 and the segment 23 has an opposing recess 43. A coiled 110 compression spring 44 lies in these recesses; the inner end of the spring exerts pres-

sure on a vertical portion 45 of a horizontal member 47, which is freely mounted on the pin 31 and in a groove 48 of the cover 8 of the casing 7. The coiled spring 44 presses the member 47 against the pin 31, which presses the frame plate 30 against the pivots 40 of the pinions. Consequently one pinion 35 is pressed against one segment 21 or 22 or 24 distally and another 36 or 37 against the segment 23 proximally.

Above the cover 8 and upon the terminal portion of the insulating pin 31, protruding therefrom, provision must be made for securing and conveniently detaching the switching member 50, as shown in Figure 4, by providing an aperture 51 through which the insulating pin 31 extends, and passing a locking pin 52, as shown in Figure 3, through an aperture 53 of the member 50 and through an aperture in the pin 31.

The member 50 presents peripherally converging sides, rounded at the localities 54, and bears a broad, arcuate, transverse slot 55 on its under surface, one arc 56 of which is convex and the other arc 60 is concave and rounded at its end portions 58 and 59. The axis of each arc is the axis of the steering wheel 6.

An actuating member 62, shown in Figure 5, is rotatably mounted upon the housing 10 of the steering column immediately above the retaining strap 11 by means of a flat ring 65. Integral with the ring 65 the arcuate plate 70 is adapted to ride upon the strap 11. The projections 67 and 68 arise from the ring 65 and are adapted to firmly engage the slots 67' and 68' of the tubular end portion 77 of the steering wheel 6. Vertical projections 73, 74 and 75 arise from the plate 70 and are adapted to rotatably engage the peripheral end portions of the member 50. The plate 70 extends between the member 50 and the cover 8 of the casing, loosely adjacent to both. The projection 75 extends into the concentric slot 55 and is freely rotatable therein, as shown in Figure 3. The projections 73 and 74, at angles of lenience disposed as to the plane 3-3, are adapted to engage the vertical sides and rounded end portions 54. An arcuate band 64 projects vertically from the ring 65 and is adapted to embrace the tubular end portion 77 of the steering wheel 6 and to support the projections 68, 73 and 74. All the numbered plates and projections of the member 65 must revolve with the steering wheel 6 around the common axis of the steering wheel 6 of the steering apparatus of a motor vehicle.

The looped strap 11 and the complementary band 11' are held, against rotary and vertical displacement upon the housing 10, by the pin 17 and the bolt 16, and hold the casing 7, against rotary and vertical displacement upon the housing 10, and vertical

to the common axis of the steering column and perpendicular to the common plane of symmetry projected in the line 3-3.

The specified construction and interaction of parts completes a mechanism for operating a pinion gear contact electric switch, adapted to connect and disconnect different sections of an internal gear, by the steering wheel as it is practically in use for directing a motor vehicle.

When the steering wheel is turned to the right the projection 74 approaches the member 50, and projection 75 emerges to the right of it without having touched it.

When the steering wheel is turned to the left the projection 73 approaches the member 50, and projection 75 emerges to the left of it without having touched it.

Short turns of the wheel are necessary for the rounding of curves or when passing vehicles, and require no signals. The angle of lenience is different for different models of motor vehicles but should be the angle at which the projections 73 and 74 stand to the line 3-3 of the plane of symmetry of the member 62.

If the steering wheel passes the angle of lenience the projection 74 impinges upon the presenting side and the portion 54 of the member 50, and the pinion 35 makes contact with the segment 24 of the internal gear, as shown in Figure 2. The coiled spring 44 acts upon the pinions 35 and 36, and holds the pinion 35 firmly in contact with segment 24, effecting a turn-to-the-right signal while the projection 74 moves on, leaving the member 50 in position for receiving a reverse impulse.

A motor vehicle having completed a turn to the right, it is necessary to stop and reverse the action of the steering wheel in order to resume a straight ahead course of the vehicle.

When the steering wheel 6 is turned, from an extreme right hand position, to the left, the projection 74 again approaches the member 50 and passes freely beyond the rounded portion 54, as shown in Figure 2. The projection 75, now next in order, impinges upon the now presenting part 54 and vertical side of the member 50, and, sliding up on the latter while pushing it out of the way, must arrive at a position opposite to the presenting opening of the slot 55 and proximally to the convexly rounded portion 59 of the same. The projection 75, proceeding to the left, must enter the slot 55 and meet the now obstructing arc 56 and sliding up on the convex surface of the arch, while pushing it out of way, must arrive between the concave arc 60 and the convex arc 56 and, together with the pinion 35, is centered upon the line 3-3 of the plane of symmetry, as shown in Figure 3.

The turn-to-the-right signal was silenced

when the pinion 35 disengaged the segment 24.

The frame plate 30, deriving resilient pressure from the coiled spring 44, urges the pivots of the pinions 35, 36 and 37 in directions parallel to the line 3—3 of the plane of symmetry. The teeth, of each pinion in mesh with the internal gear, act as levers while the gear serves as fulcrum. The parallel pressure upon the levers urges the pinions to revolve upon the internal gear in opposite directions, and balances the pinion 35 in a position of rest in equilibrium, when the pivot 40 of the same is centered upon the line 3—3, and the pinions 36 and 37 are equidistant therefrom. Applying the understood laws of leverage to rotary pinion-gear action and parallel lines of force it can be demonstrated that the pinions 35, 36 and 37 are resiliently mounted upon the internal gear and resiliently locked upon it, and that they can readily be made to revolve upon it by the drive gear 29, the shaft 31, the switching member 50, the actuating member 65 and the steering wheel 6 of a motor vehicle.

The pinions 36 and 37 may enter upon contacts with the segments 22 and 24 respectively when the member 50 is rotated either to the right or to the left to evoke such contacts, and in each instance a turn-to-the-right and a turn-to-the-left signal results. This combination of signals can be interpreted as a stop signal.

All signals are silenced by the projection 35, 75, and all signals are "set" or made by the projections 73 and 74 by the ordinary handling of the steering wheel 6, but only when turns are actually being performed.

The switching member 50, being mounted upon, and in front of, the steering column next to the steering wheel of the motor vehicle, is most accessible to the operator of the same, enabling him to "set" the proper signal by hand, if occasion arises, thereby signalling, to approaching operators of vehicles, his intention to execute a turn at the nearest intersection of his right of way, or of his necessity to stop where he is.

It is of importance to know that no signal conveys a traffic command, except the traffic officer's whistle.

A signal upon a motor vehicle is best and most useful as a direction indicator conveying the intention of the operator to make proper use of his rights upon the public highway, and as such it should be welcome and find polite response by and from all lovers of the automobile.

I claim:

1. A pinion gear contact electric switch comprising a columnar casing, a cover and a centrally protruding drive gear shaft of insulating material, a rim surrounding a tubular interior limited by planes vertical to the axis thereof, a switching member fixed

to the shaft, U-shaped loops laterally attached to the rim, a looped strap and a grooved band bent around the housing of the steering column of a motor vehicle, looped end portions of the strap hooked to the U-shaped loops of the rim, a pin adapted to fix the rim upon the grooved band and the housing, to lie in the plane laid through the axis of the tubular interior, and nuts threaded upon a bolt to tighten the strap upon the housing, rim and fixation pin, and an actuating member on the steering wheel of a motor vehicle, rotatably mounted upon the housing of a steering column comprising arcuate plates adapted to ride above the strap and over a sector of the cover of the switch casing, and a plurality of vertical projections of the arcuate plates adapted to impinge upon, push out of the way, and to rotate the switching member, and to cause pinions to connect and disconnect different segments of an internal gear of the switch, when the steering wheel of the motor vehicle is operated while the vehicle pursues its course.

2. A pinion gear contact electric switch comprising a flat casing, a cover and a centrally protruding revolving shaft of insulating material, a switching member fixed to the shaft, a rim, a plurality of vertical perforations for receiving pins and for transmitting electrically conducting wires, an electrically conducting internal gear, comprising a plurality of spaced, insulated segments, fixed to the floor and the walls of the casing, spaced and insulated as to the internal gear, and a metallic disk upon the floor, spaced and insulated from a plurality of segments, and having integral extensions adapted to electrically connect opposite, pole segments of the internal gear, and one such segment adapted to be connected by electrically conducting wires to a terminal of a battery and to transmit electric potential to the disk and the opposite pole segment, and a plurality of contact segments interposed between the pole segments.

3. A pinion gear contact electric switch fixed to a stationary housing of the steering column of a motor vehicle, comprising a casing, a segmented internal gear, a plurality of pole segments and interposed contact segments, a central metallic disk, means adapted to connect the disk with a plurality of opposite pole segments, a plurality of interconnected pivoted pinions lying upon the disk with freedom of motion thereon in mesh with the internal gear, a central drive gear lying upon the disk with freedom of motion thereon in mesh with the pinions, an insulating shaft fixed to the drive gear, a switching member adapted to be fixed upon the shaft and conveniently detached therefrom, a metallic frame plate rotatably mounted upon the shaft adapted

to maintain the resulting circular pitch line of the combined pinions in relation to the circular pitch line of the internal gear and of the drive gear, and a horizontal member rotatably mounted upon the shaft adapted to be resiliently mounted thereon and to resiliently lock the pinions upon contacts with the internal gear in any position resulting from the action of the drive gear, and an actuating member rotatably mounted upon the housing and fixed to the steering wheel adapted to rotate with the steering wheel and to actuate the switching member by automatically selected contacts with the same.

4. A pinion gear contact electric switch fixed to a stationary housing of the steering column of a motor vehicle, comprising a casing, a segmented internal gear, pole segments and interposed contact segments, a metallic disk having extensions to connect opposite pole segments, inter-connected pinions in mesh with the internal gear, a drive gear in mesh with the pinions, an insulating shaft fixed to the drive gear and a switch-

ing member fixed thereon, a metallic frame rotatably mounted upon the shaft, and upon the pinions, a resiliently mounted horizontal member rotatably mounted upon the shaft securing close contacts of the pinions upon the internal gear in all positions due to the action of the drive gear, an actuating member adapted to rotate with the steering wheel and to actuate the switching member by automatically selected contacts with the same, and means to charge the pinions with electric potential, to electrically connect and disconnect different segments, one pole segment with the opposite pole segment and with one or with another contact segment or with two contact segments, and means to selectively actuate the switching member either by hand or by automatically selected contacts of the actuating member with the switching member, and means to secure the casing upon the housing against sliding and rotary displacement comprising a looped strap, a fixation pin and a threaded bolt with nuts thereon.

CARL RUDOLPH KRONE.
